UNITED STATES PATENT OFFICE

102,690

DESIGN FOR A GLOBE CLOCK

Abe Leonard Koolish, Chicago, Ill.

Application September 30, 1936, Serial No. 65,093

Term of patent 3½ years

To all whom it may concern:

Be it known that I, Abe Leonard Koolish, a citizen of the United States and a resident of Chicago, in the county of Cook and State of Illinois, have invented a new, original, and ornamental Design for a Globe Clock, of which the following is a specification, reference being had to the accompanying drawing forming a part thereof, and in which:

Fig. 1 is a perspective view of a globe clock showing my new design; and

Fig. 2 is a top plan view of the same.

I claim:

The ornamental design for a globe clock, as shown.

ABE LEONARD KOOLISH.
